BEVERAGE DISPENSER

Bruce Kamp, Lansdowne, Pa., assignor to Monitor Process Corporation, Jersey City, N. J., a corporation of New Jersey

Application December 10, 1954, Serial No. 33,478

Term of patent 14 years

(Cl. D2—3)

Fig. 1 is a perspective view showing the front and one end of a beverage dispenser embodying my new design;

Fig. 2 is a top plan view thereof; and,

Fig. 3 is an elevational view of one end of the dispenser, the other end having the same appearance.

The back of the cabinet is plain and flat.

I claim:

The ornamental design for a beverage dispenser, as shown and described.
